UNITED STATES PATENT OFFICE.

GEORGE D. LOUDERMILTT, OF MCLEANSBORO, ILLINOIS, ASSIGNOR OF ONE-FOURTH TO JAMES M. COOPER AND ONE-FOURTH TO HARRY C. COOPER, BOTH OF MCLEANSBORO, ILLINOIS.

STOVE.

Application filed March 24, 1926. Serial No. 97,128.

This invention relates to certain novel and useful improvements in heating stoves and has for its principal object the provision of an improved construction of this character which will be highly efficient in use and economical in manufacture.

Among the several objects of the invention is the production of a fuel saving heating stove or furnace.

10 A further object of the invention is the production of a stove of the character hereinafter described wherein there is provided a simple combination and arrangement of parts for directing atmospheric air through the combustion chamber of the stove to be expelled therefrom in heated condition to circulate within the room wherein the stove is located and wherein this simple combination and arrangement of parts permits of 15 the commingling of water vapor with the atmospheric air whereby a certain amount of the water vapor may be admitted into the combustion chamber to commingle with the particles of combustion and generate an 20 inflammable gas whereby the minute particles of combustion will be entirely consumed before reaching exit through the stove pipe thus reducing the amount of soot or other unburned particles of combustion from 25 collecting in the stove pipe, thus greatly increasing the heating capacity of the stove.

30 A still further object of the invention resides in the novel combination and arrangement of parts for evaporating the water from a humidifying pan wherein this humidifying pan is located at a point near or contiguous the fire box of the stove whereby the heat generating from the fire box will come into contact with the humidifying pan and generate a water vapor which 35 passes into an air conductor leading through the combustion chamber of the stove.

40 Other objects will appear hereinafter.

45 The invention consists in the combination and arrangement of parts hereinafter described and claimed.

50 The invention will be best understood by reference to the accompanying drawing, illustrating the preferred form of construction, and in which—

Fig. 1 is a part sectional side elevational view of the stove or furnace embodying the invention,

Fig. 2 is a fragmentary sectional detail

view of the same taken substantially on line 55 2—2 of Fig. 1,

Fig. 3 is a fragmentary sectional detail view of the same taken substantially on line 3—3 of Fig. 1, and

Fig. 4 is a fragmentary sectional detail 60 view of the same taken substantially on line 4—4 of Fig. 1.

In accordance with the several objects of the invention I provide a stove, indicated generally by the reference character A. This stove includes a base 10 arranged below the fire box 11 within which the fire pot (not shown) is confined. Above this fire box the stove includes a combustion chamber 12 defined by cylindrical side walls 13 within which is formed an opening 14 through which fuel is admitted to the fire pot. This opening 14 is normally closed by a hinged door 15. The walls 13 support a top wall 16 in which is formed an opening 17 for reasons hereinafter set forth. This top wall defines an opening 18 around which is disposed an annular ring 19 adapted to receive the stove pipe 20 including the usual damper 21. This top wall 16 supports a conical deflector dome 22 which in the present instance is provided with a plurality of spaced passages 23.

Disposed in the combustion chamber 12 is a hot air conduit 24 having one end portion 25 thereof received by the opening 17. This hot air conduit extends through the combustion chamber in an outwardly and downwardly direction and through an opening 26 where the hot air conduit connects 85 with a cold air conduit 27 having an opening 28 formed in its lower end portion for admission of atmospheric air therein to pass through the hot air conduit to be heated by the heat generated in the combustion chamber. This outwardly and downwardly inclined portion of the hot air conduit is indicated at 26' and it is important to note 90 that this portion of the hot air conduit is disposed directly over the fire pot so that the heat generating from the particles of combustion in this fire pot will be directed 95 into contact with the walls of the hot air conduit at this point.

The cold air conduit 27 has an opening 100 29 formed therein above which is disposed a shield 30. This shield 30 extends inwardly and downwardly and has its outer edge 105

- portion 31 disposed to rest upon the adjacent top edge portion 31' of a humidifying pan 32. This pan 32 is supported by the cold air conduit between this conduit and the fire box 11 through the medium of a supporting shelf 33 which includes an upturned flange 34 serving to prevent self-displacement of this humidifying pan. This humidifying pan further includes a portion 35 defining a filling neck 36 through which water is admitted into the humidifying pan. This filling neck is normally closed by a spring controlled closure plate 37 of any approved construction which includes an operating handle 38.
- The portion 26' of the hot air conduit has formed therein, in its bottom wall portion 39, an opening 40 which is normally closed by a shutter plate 41 controlled by an operating handle 42 as best shown in Fig. 1. This shutter plate 41 is guided in movement, to open and close the opening 40, by a suitable guiding housing 43 carried by the bottom wall 39 on the inner side thereof.
- Carried by the portion 26' on the outer side of the bottom wall 39 is a deflector plate 44 defining a passage 45 having communication at one end as at 46 with the hot air conduit 26' through the opening 40. The upper end portion 47 of this deflector has a plurality of perforations 48 formed therein opening communication between the passage of the combustion chamber 12.
- This arrangement is such that atmospheric air admitted through the cold air conduit into the hot air conduit 26' finds entrance into the passage 45 when the shutter plate 41 is in open position. As this atmospheric air is admitted to the passage it is directed in an upward direction through the passage 45 to find exit through the perforations 48 into the combustion chamber 12 where it commingles with the particles of combustion within this combustion chamber. It is apparent that by providing the passage 45 the atmospheric air before being admitted into the combustion chamber 12 is substantially heated by the heat generating from the production of combustion within the fire pot so that as this heated air is admitted into the combustion chamber 12 through the perforations 48 it naturally follows that this heated air will rise within the combustion chamber into contact with the hot air conduit 24 thereby serving to instantly heat the air passing through this hot air conduit 24 and through the passages formed in the deflector dome. It is also apparent that with the atmospheric air entering the passage 45 from the cold air conduit 27 is carried a certain amount of water vapor from the humidifying pan and as this water vapor is admitted into the combustion chamber through the perforations 48 the moist air will tend to generate an inflammable gas

thereby assuring complete combustion of the unburned minute particles of combustion.

It is important to note that when the shutter is in position to close passage through the opening 40 that the water vapor generating from the humidifying pan will be directed through the hot air conduits 26' and 24" thus permitting a certain amount of moisture in the heated air of the room within which the stove is located. This arrangement takes the place of arranging a pan of water under the deflector dome of the stove.

As shown in Fig. 1 the wall defining the combustion chamber 12 is provided with a draft opening 49 through which atmospheric air is admitted directly to the combustion chamber for reasons well known in the art. The draft being admitted through this opening is controlled by a regulating plate 50 of any approved construction including an operating knob 51.

From the description herein it is manifest to those skilled in the art that I provide a stove wherein the heating capacity of the same is greatly increased by reason of the novel manner in which moist atmospheric air is directed through the combustion chamber to be expelled through the passages formed in the deflector dome.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A heating stove of the class described including wall portions defining a combustion chamber, an air conduit having a portion confined in the combustion chamber and a portion disposed exterior of the wall portions defining the combustion chamber, and means for admitting water vapor to the interior of the conduit to find exit through the portion of the conduit confined in the combustion chamber.

2. A heating stove of the class described including wall portions defining a combustion chamber, an air conduit having a portion confined in the combustion chamber and a portion disposed exterior of the wall portions defining the combustion chamber, and means for admitting water vapor to the interior of the conduit to find exit through the portion of the conduit confined in the combustion chamber, said means including a humidifying pan disposed between the fire box of the stove and the exterior portion of the conduit.

3. A heating stove of the class described including wall portions defining a combustion chamber, an air conduit having a portion confined in the combustion chamber and a portion disposed exterior of the wall portions defining the combustion chamber, means for admitting water vapor to the interior of the conduit to find exit through the portion of the conduit confined in the combustion chamber, and means permitting the admission of a certain amount of the water vapor into the combustion chamber of the stove.
4. A heating stove of the class described including wall portions defining a combustion chamber, an air conduit having a portion confined in the combustion chamber and a portion exterior of the combustion chamber, means for admitting water vapor to the exterior portion of the conduit to find passage through the portion of the conduit confined in the combustion chamber, means permitting the admission of a certain amount of water vapor into the combustion chamber from the portion of the conduit confined in the combustion chamber, said means including a body defining a plurality of perforations and a passage in communication through the perforations with the combustion chamber and in communication with the conduit through an opening formed in the portion of the conduit confined in the combustion chamber.
5. A heating stove, including wall portions defining a combustion chamber, an air conduit having a portion confined in the combustion chamber and a portion exterior of the combustion chamber, means for admitting water vapor to the exterior portion of the conduit to find exit through the portion of the conduit confined in the combustion chamber, means permitting the admission of a certain amount of the water vapor into the combustion chamber, said means including a body defining a plurality of perforations and a passage in communication through the perforations with the com-
- bustion chamber and in communication with the conduit through an opening formed in the portion of the conduit confined in the combustion chamber, and means controlling passage of the water vapor through said opening.
6. A heating stove of the class described including wall portions defining a combustion chamber, a conduit having a portion confined in the combustion chamber and including a portion exterior of the walls defining the combustion chamber, said exterior portions of the conduit being provided with an opening in the wall thereof, a supporting shelf carried by the said exterior portion of the conduit, a humidifying pan removably carried by the supporting shelf, and a shield carried by the said exterior portion of the conduit for directing water vapor from the humidifying pan through the opening into the conduit to find passage through the portion of the conduit confined in the combustion chamber.
7. A heating stove of the class described including wall portions defining a combustion chamber, a conduit having a portion confined in the combustion chamber and including a portion exterior of the walls defining the combustion chamber, said exterior portions of the conduit being provided with an opening in the wall thereof, a supporting shelf carried by the said exterior portion of the conduit, a humidifying pan removably carried by the supporting shelf, a shield carried by the said exterior portion of the conduit for directing water vapor from the humidifying pan through the opening into the conduit to find passage through the portion of the conduit confined in the combustion chamber, and means for permitting a certain amount of the water vapor passing through the portion of the conduit confined in the combustion chamber into the combustion chamber.

In testimony whereof I affix my signature.

GEORGE D. LOUDERMILTT.
